(57) **ABSTRACT**

In embodiments of the present invention, a method of modifying ambient sound received by an earpiece in accordance with an environmental characterization may have one or more of the following steps: (a) receiving the ambient sound at a microphone operably coupled to the earpiece, (b) determining, via a processor operably coupled to the microphone, the environmental characterization based on the ambient sound, (c) modifying, via the processor, the ambient sound in accordance with a plurality of parameters associated with the environmental characterization to create a modified ambient sound, (d) communicating, via a speaker operably coupled to the earpiece, the modified ambient sound, (e) receiving the ambient sound at the second microphone, (f) determining, via the processor, a location of the ambient sound from a temporal differential and an intensity differential between the reception of the ambient sound at the microphone and the reception of the ambient sound at the second microphone, and (g) determining, via the processor, a location of the ambient sound from a temporal differential

(Continued)

and an intensity differential between the reception of the ambient sound at the microphone of the earpiece and the reception of the ambient sound at the second microphone of the second earpiece.

**AMBIENT ENVIRONMENTAL SOUND FIELD
MANIPULATION BASED ON USER DEFINED
VOICE AND AUDIO RECOGNITION
PATTERN ANALYSIS SYSTEM AND
METHOD**

PRIORITY STATEMENT

This application claims priority to U.S. Provisional Patent Application No. 62/439,371, filed on Dec. 27, 2016, titled Ambient Environmental Sound Field Manipulation Based on User Defined Voice and Audio Recognition Pattern Analysis System and Method, all of which is hereby incorporated by reference in its entirety.

FIELD OF THE INVENTION

The present invention relates to wearable devices. Particularly, the present invention relates to earpieces. More particularly, but not exclusively, the present invention relates to wireless earpieces.

BACKGROUND

Users who wear earpieces may encounter many different environments running, jogging, or otherwise traveling during a given time period. On a daily basis people are subjected to a variety of noises of varying amplitude. These sources of noise affect a person's quality of life in a number of ways ranging from simple annoyance to noise induced fatigue and even hearing loss. Common sources of noise include those related to travel, e.g., subway trains, motorcycles, aircraft engine and wind noise, etc., and those related to one's occupation, e.g., factory equipment, chain saws, pneumatic drills, lawn mowers, hedge trimmers, etc.

To help alleviate background noise while providing a source of entertainment, many people listen to music or other audio programming via a set of earpieces. Unfortunately, the use of earpieces may also lead to problematic, even dangerous situations if the user is unable to hear the various auditory cues and warnings commonly relied upon in day to day living (e.g., warning announcements, sirens, alarms, car horns, barking dogs, etc.). Accordingly, what is needed is a system that provides its users with the benefits associated with headphones without their inherent drawbacks and limitations. Further, depending on the circumstances, a user may wish to modify how certain types of ambient sounds are heard depending on the user's location or preferences. What is needed is a system and method of ambient environmental sound field manipulation based on user defined voice and audio recognition pattern analysis.

SUMMARY

Therefore, it is a primary object, feature, or advantage of the present invention to improve over the state of the art.

In embodiments of the present invention an earpiece may have one or more of the following features: (a) an earpiece housing, (b) a first microphone operably coupled to the earpiece housing, (c) a speaker operably coupled to the earpiece housing, (d) a processor operably coupled to the earpiece housing, the first microphone, and the speaker, wherein the first microphone is positioned to receive an ambient sound, wherein the processor is programmed to characterize an environment associated with the ambient sound, and wherein the processor is programmed to modify the ambient sound based on a set of parameters associated

with the environment, and (e) a second microphone operably coupled to the earpiece housing and the processor, wherein the second microphone is positioned to receive the ambient sound.

5 In embodiments of the present invention a set of earpieces comprising a left earpiece and a right earpiece, wherein each earpiece may have one or more of the following features: (a) an earpiece housing, (b) a microphone operably coupled to the earpiece housing, (c) a speaker operably coupled to the earpiece housing, and (d) a processor operably coupled to the earpiece housing, the microphone, and the speaker, wherein each microphone is positioned to receive an ambient sound, wherein each processor is programmed to characterize an environment associated with the ambient sound, 10 wherein each processor is programmed to modify the ambient sound based on a set of parameters associated with the environment.

In embodiments of the present invention, a method of 15 modifying ambient sound received by an earpiece in accordance with an environmental characterization may have one or more of the following steps: (a) receiving the ambient sound at a microphone operably coupled to the earpiece, (b) determining, via a processor operably coupled to the microphone, the environmental characterization based on the ambient sound, (c) modifying, via the processor, the ambient sound in accordance with a plurality of parameters associated with the environmental characterization to create a modified ambient sound, (d) communicating, via a speaker operably coupled to the earpiece, the modified ambient sound, (e) receiving the ambient sound at the second microphone, (f) determining, via the processor, a location of the ambient sound from a temporal differential and an intensity differential between the reception of the ambient sound at the microphone and the reception of the ambient sound at the second microphone, and (g) determining, via the processor, a location of the ambient sound from a temporal differential and an intensity differential between the reception of the ambient sound at the microphone of the earpiece and the 20 reception of the ambient sound at the second microphone of the second earpiece.

One or more of these and/or other objects, features, or advantages of the present invention will become apparent from the specification and claims follow. No single embodiment need provide each and every object, feature, or advantage. Different embodiments may have different objects, features, or advantages. Therefore, the present invention is not to be limited to or by an object, feature, or advantage stated herein.

BRIEF DESCRIPTION OF THE DRAWINGS

FIG. 1 illustrates a block diagram of an earpiece in accordance with an embodiment of the present invention;

FIG. 2 illustrates a block diagram of an earpiece in accordance with an embodiment of the present invention;

FIG. 3 illustrates a pictorial representation of a set of earpieces in accordance with an embodiment of the present invention;

FIG. 4 illustrates a pictorial representation of a right earpiece and its relationship with a user's external auditory canal in accordance with an embodiment of the present invention;

FIG. 5 illustrates a pictorial representation of a set of earpieces and its relationship with a mobile device in accordance with an embodiment of the present invention; and

FIG. 6 illustrates a flowchart of a method of modifying an ambient sound received by an earpiece in accordance with an embodiment of the present invention.

DETAILED DESCRIPTION

The following discussion is presented to enable a person skilled in the art to make and use the present teachings. Various modifications to the illustrated embodiments will be readily apparent to those skilled in the art, and the generic principles herein may be applied to other embodiments and applications without departing from the present teachings. Thus, the present teachings are not intended to be limited to embodiments shown, but are to be accorded the widest scope consistent with the principles and features disclosed herein. The following detailed description is to be read with reference to the figures, in which like elements in different figures have like reference numerals. The figures, which are not necessarily to scale, depict selected embodiments and are not intended to limit the scope of the present teachings. Skilled artisans will recognize the examples provided herein have many useful alternatives and fall within the scope of the present teachings. While embodiments of the present invention are discussed in terms of earpieces controlling and/or modifying ambient sound, it is fully contemplated embodiments of the present invention could be used in most any electronic communications device without departing from the spirit of the invention.

It is an object, feature, or advantage of the present invention to characterize an environment associated with an ambient sound.

It is a still further object, feature, or advantage of the present invention to modify an ambient sound based on the environment the ambient sound originates.

Another object, feature, or advantage is to modify an ambient sound based on parameters associated with the environment.

Yet another object, feature, or advantage is to modify an ambient sound based on one or more user settings.

Yet another object, feature, or advantage is to automatically modify an ambient sound based on user or third party histories or preferences.

In one embodiment, an earpiece includes an earpiece housing, a microphone operably coupled to the earpiece housing, a speaker operably coupled to the earpiece housing, and a processor operably coupled to the earpiece housing, the microphone, and the speaker. The microphone is positioned to receive an ambient sound. The processor is programmed to both characterize an environment associated with the ambient sound and modify the ambient sound based on a set of parameters associated with the environment.

One or more of the following features may be included. The parameters associated with the environment may be based on user settings. The user settings may be made via voice input. A second microphone may be operably coupled to the earpiece housing and the processor and may be positioned to receive the ambient sound. The processor may determine a location of the ambient sound from a temporal differential between the reception of the ambient sound at the microphone and the reception of the ambient sound at the second microphone. The modification of the ambient sound may be automatically performed based on the set of parameters associated with the environment.

In another embodiment, a set of earpieces having a left earpiece and a right earpiece each include an earpiece housing, a microphone operably coupled to the earpiece housing, a speaker operably coupled to the earpiece housing,

and a processor operably coupled to the earpiece housing, the microphone, and the speaker. The microphone is positioned to receive an ambient sound. The processor is programmed to both characterize an environment associated with the ambient sound and modify the ambient sound based on a set of parameters associated with the environment.

One or more of the following features may be included. The parameters associated with the environment may be based on user settings. The user settings may be made via voice input. The processor may determine a location of the ambient sound from a temporal differential between the reception of the ambient sound at the microphone of the left earpiece and the reception of the ambient sound at the microphone of the right earpiece. The modification of the ambient sound may be automatically performed based on the set of parameters associated with the environment.

In another embodiment, a method of modifying an ambient sound received by an earpiece in accordance with an environmental characterization includes receiving the ambient sound at a microphone operably coupled to the earpiece, determining the environmental characterization based on the ambient sound using a processor operably coupled to the earpiece, modifying the ambient sound in accordance with a plurality of parameters associated with the environmental characterization to create a modified ambient sound using the processor operably coupled to the earpiece, and communicating the modified ambient sound using a speaker operably coupled to the earpiece.

One or more of the following features may be included. The parameters associated with the environmental characterization may be based on user settings. The user settings may be made via voice input. The user settings may include location data, user history, user preferences, third party history or third party preferences. The earpiece may further include a second microphone. The ambient sound may be received at the second microphone. The processor may determine a location of the ambient sound from a temporal differential and an intensity differential between the reception of the ambient sound at the microphone and the reception of the ambient sound at the second microphone. The ambient sound may be received by a second earpiece having a second microphone. The processor may determine a location of the ambient sound from a temporal differential and an intensity differential between the reception of the ambient sound at the microphone of the earpiece and the reception of the ambient sound at the second microphone of the second earpiece.

FIG. 1 illustrates a block diagram of an earpiece 10 having an earpiece housing 12, a microphone 14 operably coupled to the earpiece housing 12, a speaker 16 operably coupled to the earpiece housing 12, and a processor 18 operably coupled to the earpiece housing 12, the microphone 14, and the speaker 16. The microphone 14 is positioned to receive an ambient sound and the processor 18 is programmed to characterize an environment associated with the ambient sound and modify the ambient sound based on a set of parameters associated with the environment. Each of the aforementioned components may be arranged in any manner suitable to implement the earpiece 10.

The earpiece housing 12 may be composed of plastic, metallic, nonmetallic, or any material or combination of materials having substantial deformation resistance in order to facilitate energy transfer if a sudden force is applied to the earpiece 10. For example, if the earpiece 10 is dropped by a user, the earpiece housing 12 may transfer the energy received from the surface impact throughout the entire earpiece. In addition, the earpiece housing 12 may be

capable of a degree of flexibility in order to facilitate energy absorbance if one or more forces is applied to the earpiece 10. For example, if an object is dropped on the earpiece 12, the earpiece housing 12 may bend in order to absorb the energy from the impact so the components within the earpiece 10 are not substantially damaged. The flexibility of the earpiece housing 12 should not, however, be flexible to the point where one or more components of the earpiece 10 may become dislodged or otherwise rendered non-functional if one or more forces is applied to the earpiece 10.

A microphone 14 is operably coupled to the earpiece housing 12 and the processor 18 and is positioned to receive ambient sounds. The ambient sounds may originate from an object worn or carried by a user, a third party, or the environment. Environmental sounds may include natural sounds such as thunder, rain, or wind or artificial sounds such as sounds made by machinery at a construction site. The type of microphone 14 employed may be a directional, bidirectional, omnidirectional, cardioid, shotgun, or one or more combinations of microphone types, and more than one microphone may be present in the earpiece 10. If more than one microphone is employed, each microphone 14 may be arranged in any configuration conducive to receiving an ambient sound. In addition, each microphone 14 may comprise an amplifier and/or an attenuator configured to modify sounds by either a fixed factor or in accordance with one or more user settings of an algorithm stored within a memory or the processor 18 of the earpiece 10. For example, a user may issue a voice command to the earpiece 10 via the microphone 14 to instruct the earpiece 10 to amplify sounds having sound profiles substantially similar to a human voice and attenuate sounds exceeding a certain sound intensity. The user may also modify the user settings of the earpiece 10 using a voice command received by one of the microphones 14, a control panel or gestural interface on the earpiece 10, or a software application stored on an external electronic device such as a mobile phone or a tablet capable of interfacing with the earpiece 10. Sounds may also be amplified or attenuated by an amplifier or an attenuator operably coupled to the earpiece 10 and separate from the microphones 14 before being communicated to the processor 18 for sound processing.

A speaker 16 is operably coupled to the earpiece housing 12 and the processor 18. The speaker 16 may produce ambient sounds modified by the processor 18 or one or more additional components of the earpiece 10. The modified ambient sounds produced by the speaker 16 may include modified sounds made by an object worn or carried by the user, one or more amplified human voices, one or more attenuated human voices, one or more amplified environmental sounds, one or more attenuated environmental sounds, or a combination of one or more of the aforementioned modified sounds. In addition, the speaker 16 may produce additional sounds such as music or a sporting event either stored within a memory of the earpiece 10 or received from a third party electronic device such as a mobile phone, tablet, communications tower, or a WiFi hotspot in accordance with one or more user settings. For example, the speaker 16 may communicate music communicated from a radio tower of a radio station at a reduced volume in addition to communicating or producing certain artificial noises such as noises made by heavy machinery when in use. In addition, the speaker 16 may be positioned proximate to a temporal bone of the user in order to conduct sound for people with limited hearing capacity. More than one speaker 16 may be operably coupled to the earpiece housing 12 and the processor 18.

The processor 18 is operably coupled to the earpiece housing 12, the microphone 14, and the speaker 16 and is programmed to characterize an environment associated with the ambient sound. The characterization of the environment by the processor 18 may be performed using the ambient sounds received by the microphone 14. For example, the processor 18 may use a program or an algorithm stored in a memory or the processor 18 itself on the ambient sound to determine or approximate the environment in which jack-hammer sounds, spoken phrases such as "Don't drill too deep!", or other types of machinery sounds originate, which in this case may be a construction site or a road repair site. In addition, the processor 18 may use sensor readings or information encoded in a signal received by a third party electronic device to assist in making the characterization of the environment. For example, in the previous example, the processor may use information encoded in a signal received from a mobile device using a third party program such as Waze to determine the ambient sounds come from a water main break is causing a severe traffic jam. In addition, the processor 18 is programmed to modify the ambient sound based on a set of parameters associated with the environment. The modification may be performed in accordance with one or more user settings. The user settings may include, for example, to amplify the sounds of speech patterns if the sound level of the origin of the sounds is low, to attenuate the sounds of machinery if the sounds exceed a certain decibel level, to remove all echoes regardless of environment, or to filter out sounds having a profile similar to crowd noise when attending a live entertainment event. The set of parameters may also be based on one or more sensor readings, one or more sounds, or information encoded in a signal received by a transceiver.

FIG. 2 illustrates another embodiment of the earpiece 10. In addition to the elements described in FIG. 1 above, the earpiece 10 may further include a memory 20 operably coupled to the earpiece housing 12 and the processor 18, wherein the memory 20 stores various programs, applications, and algorithms used to characterize an environment associated with the ambient sound and modify the ambient sound, one or more sensors 22 operably coupled to the earpiece housing 12 and the processor 18, a wireless transceiver 24 disposed within the earpiece housing 12 and operably coupled to the processor 18, a gesture interface 26 operably coupled to the earpiece housing 12 and the processor 18, a transceiver 28 disposed within the earpiece housing 12 and operably coupled to the processor 18, one or more LEDs 30 operably coupled to the earpiece housing 12 and the processor 18, and an energy source 36 disposed within the earpiece housing 12 and operably coupled to each component within the earpiece 10. The earpiece housing 12, the microphone 14, the speaker 16, and the processor 18 all function substantially the same as described in FIG. 1, with differences in regards to the additional components as described below.

Memory 20 may be operably coupled to the earpiece housing 12 and the processor 18 and may have one or more programs, applications, or algorithms stored within may be used in characterizing an environment associated with an ambient sound or modifying the ambient sound based on a set of parameters associated with the environment utilizing environmental characterization 100. For example, the memory 20 may have a program which compares sound profiles of ambient sounds received by the microphone 14 with one or more sound profiles of certain types of environments. If the sound profile of an ambient sound substantially matches one of the sound profiles in the memory 20

when the program is executed by the processor **18**, then the processor **18** may determine an environment is successfully characterized with the ambient sound. In addition, the memory **20** may have one or more programs or algorithms to modify the ambient sound in accordance with a set of parameters associated with the environment. For example, if the user desires the converse with someone while wearing an earpiece, then the processor **18** may execute a program or application stored on the memory **20** to attenuate or eliminate all ambient sounds not substantially matching a sound profile similar to the sound of a human voice. The memory **20** may also have other programs, applications, or algorithms stored within are not related to characterizing an environment or modifying an ambient sound.

The memory **20** is a hardware component, device, or recording media configured to store data for subsequent retrieval or access at a later time. The memory **20** may be static or dynamic memory. The memory **20** may include a hard disk, random access memory, cache, removable media drive, mass storage, or configuration suitable as storage for data, instructions and information. In one embodiment, the memory **20** and the processor **18** may be integrated. The memory **18** may use any type of volatile or non-volatile storage techniques and mediums. The memory **18** may store information related to the status of a user and other peripherals, such as a mobile phone **60** and so forth. In one embodiment, the memory **20** may display instructions or programs for controlling the gesture control interface **26** including one or more LEDs or other light emitting components **32**, speakers **16**, tactile generators (e.g., vibrator) and so forth. The memory **20** may also store the user input information associated with each command. The memory **20** may also store default, historical or user specified information regarding settings, configuration or performance of the earpieces **10** (and components thereof) based on the user contact with contacts sensor(s) **22** and/or gesture control interface **26**.

The memory **20** may store settings and profiles associated with users, speaker settings (e.g., position, orientation, amplitude, frequency responses, etc.) and other information and data may be utilized to operate the earpieces **10**. The earpieces **10** may also utilize biometric information to identify the user so settings and profiles may be associated with the user. In one embodiment, the memory **20** may include a database of applicable information and settings. In one embodiment, applicable gesture information received from the gesture interface **26** may be looked up from the memory **20** to automatically implement associated settings and profiles.

One or more sensors **22** may be operably coupled to the earpiece housing **12** and the processor **18** and may be positioned or configured to sense various external stimuli used to better characterize an environment. One or more sensors **22** may include a chemical sensor **38**, a camera **40** or a bone conduction sensor **42**. For example, if the microphone **14** picks up ambient sounds consisting of a blazing fire but a chemical sensor **38** does not sense any smoke, this information may be used by the processor **18** to determine the user is not actually near a blazing fire, but may be in a room watching a television program currently showing a blazing fire. In addition, an image or video captured by a camera **40** may be employed to better ascertain an environment associated with an ambient sound. A bone conduction sensor **42** may also be used to ascertain whether a sound originates from the environment or the user. For example, in order to differentiate whether a voice originates from a third party or the user, a timing difference between when the voice

reaches the microphone **14** and when the voice reaches the bone conduction sensor **42** may be used by the processor **18** to determine the origin of the voice. Other types of sensors may be employed to improve the capabilities of the processor **18** in characterizing an environment associated with one or more ambient sounds.

Wireless transceiver **24** may be disposed within the earpiece housing **12** and operably coupled to the processor **18** and may receive signals from or transmit signals to another electronic device. The signals received by the wireless transceiver **24** may encode data or information related to a current environment or parameters associated with the environment. For example, the wireless transceiver **24** may receive a signal encoding information regarding the user's current location, which may be used by the processor **18** in better characterizing an environment. The information may come from a mobile device, a tablet, a communications tower such as a radio tower, a WiFi hotspot, or another type of electronic device. In addition, the wireless transceiver **24** may receive signals encoding information concerning how the user wants an ambient sound modified. For example, a user may use a program on a mobile device such as a smartphone **60** to instruct the earpiece **10** to attenuate a loud uncle's voice if the microphone **14** receives such a sound and transmit the instructions to the memory **20** or processor **18** of the earpiece **10** using the smartphone, which may be received by the wireless transceiver **24** before being received by the processor **18** or memory **20**. The wireless transceiver **24** may also receive signals encoding data related to media or information concerning news, current events, or entertainment, information related to the health of a user or a third party, information regarding the location of a user or third party, or information concerning the functioning of the earpiece **10**. More than one signal may be received from or transmitted by the wireless transceiver **24**.

Gesture interface **26** may be operably coupled to the earpiece housing **12** and the processor **18** and may be configured to allow a user to control one or more functions of the earpiece **10**. The gesture interface **26** may include at least one emitter **32** and at least one detector **34** to detect gestures from either the user, a third party, an instrument, or a combination of the aforementioned and communicate one or more signals representing the gesture to the processor **18**. The gestures may be used with the gesture interface **26** to control the earpiece **10** including, without limitation, touching, tapping, swiping, use of an instrument, or any combination of the aforementioned gestures. Touching gestures used to control the earpiece **10** may be of any duration and may include the touching of areas not part of the gesture interface **26**. Tapping gestures used to control the earpiece **10** may include any number of taps and need not be brief. Swiping gestures used to control the earpiece **10** may include a single swipe, a swipe changes direction at least once, a swipe with a time delay, a plurality of swipes, or any combination of the aforementioned. An instrument used to control the earpiece **10** may be electronic, biochemical or mechanical, and may interface with the gesture interface **26** either physically or electromagnetically.

Transceiver **28** may be disposed within the earpiece housing **12** and operably coupled to the processor **18** and may be configured to send or receive signals from another earpiece if the user is wearing an earpiece **10** in both ears. The transceiver **28** may receive or transmit more than one signal simultaneously. For example, a transceiver **28** in an earpiece **10** worn at a right ear may transmit a signal encoding instructions for modifying a certain ambient sound (e.g. thunder) to an earpiece **10** worn at a left ear while

receiving a signal encoding instructions for modifying crowd noise from the earpiece **10** worn at the left ear. The transceiver **28** may be of any number of types including a near field magnetic induction (NFC) transceiver.

LEDs **30** may be operably coupled to the earpiece housing **12** and the processor **18** and may be configured to provide information concerning the earpiece **10**. For example, the processor **18** may communicate a signal encoding information related to the current time, the battery life of the earpiece **10**, the status of another operation of the earpiece **10**, or another earpiece function to the LEDs **30**, which may subsequently decode and display the information encoded in the signals. For example, the processor **18** may communicate a signal encoding the status of the energy level of the earpiece, wherein the energy level may be decoded by LEDs **30** as a blinking light, wherein a green light may represent a substantial level of battery life, a yellow light may represent an intermediate level of battery life, a red light may represent a limited amount of battery life, and a blinking red light may represent a critical level of battery life requiring immediate recharging. In addition, the battery life may be represented by the LEDs **30** as a percentage of battery life remaining or may be represented by an energy bar having one or more LEDs, wherein the number of illuminated LEDs represents the amount of battery life remaining in the earpiece. The LEDs **30** may be located in any area on the earpiece **10** suitable for viewing by the user or a third party and may also consist of as few as one diode which may be provided in combination with a light guide. In addition, the LEDs **30** need not have a minimum luminescence.

Energy source **36** is operably coupled to all of the components within the earpiece **10**. The energy source **36** may provide enough power to operate the earpiece **10** for a reasonable duration of time. The energy source **36** may be of any type suitable for powering earpiece **10**. However, the energy source **36** need not be present in the earpiece **10**. Alternative battery-less power sources, such as sensors configured to receive energy from radio waves (all of which are operably coupled to one or more earpieces **10**) may be used to power the earpiece **10** in lieu of an energy source **36**.

FIG. 3 illustrates a pair of earpieces **50** which includes a left earpiece **50A** and a right earpiece **50B**. The left earpiece **50A** has a left earpiece housing **52A**. The right earpiece **50B** has a right earpiece housing **52B**. The left earpiece **50A** and the right earpiece **50B** may be configured to fit on, at, or within a user's external auditory canal and may be configured to substantially minimize or completely eliminate external sound capable of reaching the tympanic membrane. The earpiece housings **52A** and **52B** may be composed of any material with substantial deformation resistance and may also be configured to be soundproof or waterproof. A microphone **14A** is shown on the left earpiece **50A** and a microphone **14B** is shown on the right earpiece **50B**. The microphones **14A** and **14B** may be located anywhere on the left earpiece **50A** and the right earpiece **50B** respectively and each microphone may be positioned to receive one or more ambient sounds from an object worn or carried by the user, one or more third parties, or the outside environment, whether natural or artificial. A second microphone **46A** may also be included on an earpiece such as left earpiece **50A** in order to ascertain a probable origin of an ambient sound when used in conjunction with microphone **14A**. Speakers **16A** and **16B** may be configured to communicate modified ambient sounds **54A** and **54B**. The modified ambient sounds **54A** and **54B** may be communicated to the user, a third party, or another entity capable of receiving the communicated sounds. Speakers **16A** and **16B** may also be configured to

short out if the decibel level of the processed sounds **54A** and **54B** exceeds a certain decibel threshold, which may be preset or programmed by the user or a third party.

FIG. 4 illustrates a side view of the right earpiece **50B** and its relationship to a user's ear. The right earpiece **50B** may be configured to both minimize the amount of external sound reaching the user's external auditory canal **56** and to facilitate the transmission of the modified ambient sound **54B** from the speaker **16B** to a user's tympanic membrane **58**. The right earpiece **50B** may also be configured to be of any size necessary to comfortably fit within the user's external auditory canal **56** and the distance between the speaker **16B** and the user's tympanic membrane **58** may be any distance sufficient to facilitate transmission of the modified ambient sound **54B** to the user's tympanic membrane **58**. A sensor **22B**, which may include a chemical sensor **38** or a camera **40**, may be placed on the right earpiece **50B** and may be positioned to sense one or more pieces of data related to the environment. For example, the sensor **22B** may be positioned on the right earpiece **50B** to capture one or more images, detect the presence of one or more chemicals, or detect the presence of one or more additional environmental physical characteristics, all of which may be used to modify one or more ambient sounds received by the microphone **14B** in conjunction with one or more parameters, which may include user settings or data contained in programs or algorithms stored in a memory operably coupled to the right earpiece **50B** to modify or manipulate one or more ambient sounds for communication to the user's tympanic membrane **58**. In addition, a bone conduction microphone **42B** may be positioned near the temporal bone of the user's skull in order to sense a sound from a part of the user's body or to sense one or more sounds before the sounds reach one of the microphones **14** and/or **46** in order to determine if a sound is an ambient sound from the environment or if the sound originated from the user. The gesture interface **26B** may provide for gesture control by the user or a third party such as by tapping or swiping across the gesture interface **26B**, tapping or swiping across another portion of the right earpiece **50B**, providing a gesture not involving the touching of the gesture interface **26B** or another part of the right earpiece **50B**, or through the use of an instrument configured to interact with the gesture interface **26B**. The user may use the gesture interface **26B** to set or modify one or more user settings to be used in conjunction with the modification of one or more ambient sounds.

FIG. 5 illustrates a pair of earpieces **50** and their relationship to a mobile device **60**. The mobile device **60** may be a mobile phone, a tablet, a watch, a PDA, a remote, an eyepiece, an earpiece, or any electronic device not requiring a fixed location. The user may use a software application on the mobile device **60** to set one or more user settings to be used to modify or manipulate one or more ambient sounds received by one of the earpieces. For example, the user may use a software application on the mobile device **60** to access a screen allowing the user to amplify low frequency sounds, filter high frequency sounds, attenuate crowd noise, or otherwise modify various types of ambient sounds. Sound profiles of various types of ambient sounds may be present on the mobile device **60** or may require downloading from an external electronic device. In addition, the user may use the mobile device **60** to set the pair of earpieces **50** to automatically modify certain environmental sounds, such as echoes, when received by one or more of the microphones **14** and/or **46** of the pair of earpieces **50**.

FIG. 6 illustrates a flowchart of a method of modifying an ambient sound received by an earpiece in accordance with

11

an environmental characterization 100. First in step 102, an ambient sound is received by a microphone 14 operably coupled to the earpiece 50. The ambient sound may originate from an object worn or carried by the user, a third party, a natural environmental phenomenon such as thunder or rain or man-made objects such as machinery, and more than one ambient sound may be received by the microphone 14. In addition, the microphone 14 may receive one or more of the ambient sounds continuously or discretely depending on when the ambient sounds are created or communicated.

In step 104, the ambient sound may be received by a second microphone 46 operably coupled to the earpiece 50 or, if the user is wearing a pair of earpieces 50, the microphone 46 of the other earpiece 50. In step 106, if a sensor 22 is operably coupled to the earpiece 50, sensor readings may be received by the sensor 22 concerning the approximate origin of the ambient sound. Sensor readings may include images or video captured by a camera 40, gas concentration readings by a chemical sensor 38, or sounds captured by a bone conduction microphone 42. Other types of sensor reading may be used if they help in characterizing an environment.

In step 108, if a wireless transceiver 24 is operably coupled to the earpiece 50, then information concerning the approximate origin may be received by the wireless transceiver 24. This information may be received before, during, or after the creation or communication of the ambient sound, and information concerning the approximate origin of an ambient sound may be stored in a memory 20. If one or more ambient sounds is received by a second microphone 46, one or more sensor readings is received by a sensor 22, or information is received via the wireless transceiver 24, then in step 110, an approximate origin of the ambient sound may be determined. The approximate origin may be determined using an algorithm stored on a memory 20 or processor 18 within the earpiece 50, wherein the algorithm may determine the approximate origin using the temporal differences between when the ambient sound was received by each microphone 14 and 46, the differences in sound intensities between the sounds received by each microphone 14 and 46, the geometry of the user's physical features, the geometry and physical characteristics of each earpiece 50, potential differences in the waveform of the ambient sounds due to the angle the ambient sounds hitting the microphones 14 and 46, chemical readings captured by a sensor 38, images or videos captured by a camera 40, information from an external electronic device such as a mobile phone 60, a tablet, or a WiFi hotspot, or other physical parameters useful in ascertaining the approximate origin of the ambient sound.

Regardless of whether additional information was received by another component of the earpiece 50, in step 112, a processor 18 operably coupled to the earpiece 50 determines an environmental characterization based on the ambient sound. The determination of the environmental characterization may be performed using a program, application, or algorithm stored within a memory 20 operably coupled to the earpiece 50. The environmental characterization may be evident from the ambient sound itself or may require additional information. The additional information may come from a sensor reading, one or more images, data or information stored in a memory 20 or data or information encoded in a signal received by a transceiver 28 or wireless transceiver 24.

In step 114, the processor modifies the ambient sound in accordance with one or more parameters associated with the environmental characterization to create a modified ambient sound 54. The parameters may be derived from the ambient

12

sounds themselves (e.g. a third party stipulating a crowd may be loud), sensor readings (e.g. images sensed by a sensor 22 and processed by a processor 18 may show an area is a crowded stadium), or information stored in a memory 20 or received from a mobile device 60 (e.g. user settings stipulating to attenuate mechanical noises when entering a construction site). The parameters may also be based on location data, user history, user preferences, one or more third party histories, or one or more third party preferences 10 of the user. For example, if the user has repeatedly set sounds when in a grocery store to be amplified, the processor 18 may automatically apply the same settings when the user encounters a grocery store. Whether a user encounters a grocery store may be determined using a voice input, a sensor reading, or an analysis of ambient sounds originating in the location, which may suggest a grocery store. In step 15 116, the modified ambient sound is communicated via a speaker 16 operably coupled to the earpiece 50. The modified ambient sounds may be communicated as they are 20 processed by the processor 18 or may be stored for later use.

The invention is not to be limited to the particular embodiments described herein. The foregoing description has been presented for purposes of illustration and description. It is not intended to be an exhaustive list or limit any 25 of the invention to the precise forms disclosed. It is contemplated other alternatives or exemplary aspects are considered included in the invention. The description is merely examples of embodiments, processes or methods of the invention. It is understood any other modifications, substitutions, and/or additions can be made, which are within the 30 intended spirit and scope of the invention.

What is claimed is:

1. An earpiece comprising:
an earpiece housing;
a first microphone operably coupled to the earpiece housing;
a second microphone operably coupled to the earpiece housing, wherein the second microphone is positioned to receive the ambient sound;
a sensor for detecting an environmental parameter to provide contextual information in addition to sound;
a speaker operably coupled to the earpiece housing; and
a processor operably coupled to the earpiece housing, the first microphone, the second microphone, and the speaker,
wherein the processor determines a location of the ambient sound from a temporal differential between the reception of the ambient sound at the first microphone and the reception of the ambient sound at the second microphone;
wherein the first microphone is positioned to receive an ambient sound;
wherein the processor is programmed to characterize an environment associated with the ambient sound using the ambient sound, sensor data for detecting the environment and user location data, user history, user preferences, and third party history or third-party preferences; and
wherein the processor is programmed to modify the ambient sound based on a set of parameters associated with the environment and communicate, via the speaker, the modified ambient sound.
2. The earpiece of claim 1 wherein the parameters associated with the environment are based on user settings.
3. The earpiece of claim 2 wherein the user settings are made via voice input.

13

4. The earpiece of claim 1 wherein the modification of the ambient sound based on the set of parameters associated with the environment is performed automatically.

5. A set of earpieces comprising a left earpiece and a right earpiece, wherein each earpiece comprises:

an earpiece housing;
a microphone operably coupled to the earpiece housing;
a sensor for detecting an environmental parameter to provide contextual information in addition to sound;
a speaker operably coupled to the earpiece housing; and
a processor operably coupled to the earpiece housing, the microphone, and the speaker, wherein the processor determines a location of the ambient sound from the reception of the ambient sound at the microphone of the left earpiece and the reception of the ambient sound at the microphone of the right earpiece; wherein each microphone is positioned to receive an ambient sound; wherein each processor is programmed to characterize an environment associated with the ambient sound using the ambient sound and sensor data for detecting the environment and user settings; and wherein each processor is programmed to modify the ambient sound based on a set of parameters associated with the environment and communicate, via the speaker, the modified ambient sound.

10 6. The set of earpieces of claim 5 wherein the parameters associated with the environment are based on the user settings.

7. The set of earpieces of claim 6 wherein the user settings are made via voice input.

15 8. The set of earpieces of claim 5 wherein the modification of the ambient sound based on the set of parameters associated with the environment is performed automatically.

9. A method of modifying ambient sound received by an earpiece in accordance with an environmental characterization comprising the steps of:

30 receiving the ambient sound at a first microphone and a second microphone operably coupled to the earpiece;

14

detecting an environmental parameter utilizing a sensor to provide contextual information in addition to sound; determining, via a processor operably coupled to the microphones, the environmental characterization based on the ambient sound;

5 determining, via the processor, a location of the ambient sound from a temporal differential and an intensity differential between the reception of the ambient sound at the first microphone and the reception of the ambient sound at the second microphone;

10 characterizing an environment associated with the ambient sound using the ambient sound and the sensor data for detecting the environment and user settings;

15 modifying, via the processor, the ambient sound in accordance with a plurality of parameters associated with the environmental characterization to create a modified ambient sound; and

20 communicating, via a speaker operably coupled to the earpiece, the modified ambient sound.

10. The method of claim 9 wherein the user settings are made via voice input.

25 11. The method of claim 10 wherein the user settings comprise location data, user history, user preferences, third party history, or third-party preferences.

12. The method of claim 9 wherein the earpiece further comprises a second microphone.

30 13. The method of claim 12 further comprising the step of receiving the ambient sound at the second microphone.

14. The method of claim 9 wherein the ambient sound is received by a second earpiece, wherein the second earpiece comprises a second microphone.

35 15. The method of claim 14 further comprising determining, via the processor, a location of the ambient sound from a temporal differential and an intensity differential between the reception of the ambient sound at the microphone of the earpiece and the reception of the ambient sound at the second microphone of the second earpiece.
